UNITED STATES PATENT OFFICE.

BENJAMIN F. MADISON AND ELBERT C. KRUME, OF COUNCIL BLUFFS, IOWA.

FEED-WATER-HEATING SYSTEM.

Application filed July 6, 1926. Serial No. 120,845.

Our invention relates to improvements in feed water heating systems wherein the feed water is inducted through the fire box and into the water space of the boiler. The 5 objects of our invention are, first, to deliver the water into the boiler of a steam engine at a much higher temperature than has heretofore been attainable; second, to provide a circulation in the heating tube 10 of the feed water with the boiler water; third, to provide a means for the greater circulation of the water in the boiler when not being supplied with feed water; fourth, to provide a quick and easy means of 15 connecting the return pipes and the injectors for the purpose of cleaning of the heating tube for the feed water; and, fifth, to provide a quick and easy means for cutting out the circulatory system connected with said 20 feed water supply.

We attain these objects by the device illustrated in the accompanying drawing, in which—

Figure 1 is a side elevation of a boiler 25 with our device attached; and Fig. 2, a plan view of our device showing the injectors attached.

Similar numerals refer to similar parts throughout the several views.

30 A water tight opening is supplied in the front sheet of the fire box at 15, through which opening is passed a corrugated pipe 3 forming a section of a longitudinal supply pipe composed of the said pipe section 3 and a pipe section 4. This pipe 3 is screwed into a ground joint coupling 14 which is 35 ground into a ring 11 welded to the back head of the fire box 8. A flanged coupling 13 is attached to the ground coupling 14 and the feed pipe 4 is located entirely within 40 the boiler shell. The feed pipe 4 is screwed into the coupling 13. The coupling 14 makes a ground joint with ring 11. The corrugated supply pipe 3 is placed immediately below the crown sheet 16 in the fire 45 box of the boiler, whose shell is 9. Externally arranged longitudinally disposed return pipes 5 and 5' are located at opposite sides of the boiler and their front ends 50 are connected with the lower portion of the shell 9 of the boiler at the front end thereof and their rear ends are connected with the supply pipe 3, 4 in rear of the fire box exteriorly of the same. The return 55 pipes 5 and 5' are provided near their front

ends with cut off valves 12 and 12' and are equipped near their rear ends with cut off valves 6 and 6'. The return pipes extend horizontally from the front portion of the boiler to the rear end thereof and are provided at opposite sides of the fire box with downwardly offset portions which extend to points in rear of the fire box and the said return pipes have rear transverse portions which are connected with the supply 60 pipe. The supply pipe extends through the fire box into the boiler and extends along the same interiorly thereof to a point midway between the ends of the boiler. A check valve 2 is arranged in the supply pipe in rear of 65 the point where the transverse portions of the return pipes are connected to the supply pipe. A pair of injectors 1 and 1' are connected with the supply pipe at the rear end thereof. A cut-off 17^a is supplied at the 70 outermost end of the supply pipe 3 and usually two injectors are supplied at the connection with said cut-off 17^a to the supply pipe 3. The injectors have their water supply pipes 18 and 18' and their steam supply 75 17 and 17', respectively.

When it is desired to feed the boiler water one or both of the injectors 1 and 1', are put in operation. The cut-off 17 is opened. The water will be forced through 80 the check valve 2 into the supply pipe 3 which is already carrying a supply of water from the return pipes 5 and 5' through the fire box into the middle position of the boiler whose shell is 9. Thus will the feed 85 water be heated before flowing into the hot water of the boiler. By reason of the larger surface proportionate to the amount of water conveyed through the supply pipe 3, the temperature of the water will be brought 90 up to a higher heat than that heated by the surrounding sheets of the fire box, and hence the feed water will be brought up to a temperature equal to or greater than that of the other water in the boiler. The cut-offs 95 12, 6 and 12' and 6' are used only in emergency when something happens to the return pipes 5 or 5' of the boiler. Thus, when the supply pipe 3 is not being used to feed the boiler through the injectors 1 and 1', its 100 temperature will be kept down by the supply of water from the cooler portion of the forward end of the boiler and near the bottom, and the heating surface of the supply pipe will be used to increase the heat of 110

the water received from the return pipes 5 and 5' so that the supply pipe 3 will not burn out.

Of course it will readily be observed that the return pipes 5 and 5' may be returned from any part of the boiler, as from the front head of the boiler, but we prefer to return them from the front and cooler part of the water of the boiler.

10 What we desire to claim and secure by Letters Patent is:

1. The combination with a locomotive boiler having a fire box, of a longitudinal supply pipe having a portion extending forwardly and upwardly through the fire box at a point beneath the crown sheet of the same and passing through the tube sheet into the boiler and extending forwardly in the barrel of the boiler to a point intermediate 15 of the ends of the same, a pair of longitudinally disposed exteriorly arranged pipes located at opposite sides of the boiler and connected at their front ends to the boiler at the lower portion of the same and above the bottom thereof and extending horizontally to points adjacent the fire box and provided thereat with transversely disposed rear portions connected to the supply pipe in rear of the fire box, a pair of transversely disposed injectors connected to the supply pipe in rear of the said transverse portions of the exterior pipes, and independent means for controlling the flow of water through the supply pipe and the exterior pipes.

35 2. The combination with a locomotive boiler having a fire box, of a longitudinal supply pipe having a portion arranged at an inclination and extending forwardly and upwardly through the fire box beneath the crown sheet of the same and passing through the tube sheet into the boiler barrel, said supply pipe extending forwardly within the

boiler to a point intermediate the ends of the same, a pair of longitudinally disposed exteriorly arranged pipes located at opposite sides of the boiler and connected at their front ends to the boiler at the lower portion of the same above the bottom thereof and extending horizontally to points at opposite sides of the fire box, said exterior pipes being provided in rear of the fire box with transversely disposed portions connected to the supply pipe at the rear portion thereof, means located in rear of the fire box and communicating with the supply pipe for supplying water to the same and for stimulating circulation through the said pipes.

3. The combination with a locomotive boiler having a fire box, of a longitudinal supply pipe having a portion arranged at an inclination and extending forwardly and upwardly through the fire box beneath the crown sheet of the same and passing through the tube sheet into the boiler barrel, a pair of longitudinally disposed exteriorly arranged pipes located at opposite sides of the boiler and connected at their front ends to the boiler at the lower portion of the same and above the bottom thereof and extending horizontally to points at opposite sides of the fire box, said exterior pipes being provided in rear of the fire box with transversely disposed portions connected to the supply pipe at the rear portion thereof, means located in rear of the transverse portions of the exterior pipes and connected with the supply pipe for supplying water to the same and for stimulating circulation through the said pipes, and independent means for controlling the flow of water through the exterior pipes and through the supply pipes.
